GEORGE B. HAGGARD, OF WAYCROSS, GEORGIA.

LINING FOR FIREPLACES.

1,069,944.

Specification of Letters Patent. Patented Aug. 12, 1913.

Application filed March 7, 1913. Serial No. 752,626.

To all whom it may concern:

Be it known that I, GEORGE B. HAGGARD, a citizen of the United States, residing at Waycross, in the county of Ware and State 5 of Georgia, have invented certain new and useful Improvements in Lining for Fireplaces, of which the following is a specification.

This invention relates to fireplaces, and 10 its object is to provide a novel and improved lining therefor, the same being simple in construction and easily mounted in place, and, furthermore, to provide a sectional lining which can be readily assembled and 15 which is strong and durable.

The invention is illustrated in the accompanying drawing in which—

Figure 1 is a cross-section of the lining; Fig. 2 is a rear elevation thereof; Fig. 3 is a 20 horizontal section on the line 3—3 of Fig. 2, and Fig. 4 is a perspective view of the rear wall sections and one of the side walls of the lining, separated.

Referring specifically to the drawing, the 25 lining comprises two opposite side walls 5, and a back wall which is in two sections, indicated at 6 and 7, respectively. These parts are separately connected and a sectional lining is thus had. The following means are 30 provided for joining the sections: On the inner faces of the side walls 5 are outstanding dovetailed ribs 8 which are adapted to enter corresponding grooves 9 in the side edges of the side wall section 6. The side 35 walls also have similar ribs 10 for holding the back wall section 7. The back of the wall section 7 is cut away as indicated at 11 to enable the grooved edges of said section to be placed between the ribs 8 and 10 after 40 which the section is slipped down in place with the ribs 10 engaging the grooves. The back of the section 6 is also recessed, as indicated at 12, to facilitate the engagement of the ribs 8 with the grooves 9. The section

7 comes flush with the bottom of the side 45 walls 5, and on its front face are lugs 13 for supporting a grate. The side walls 5 converge slightly outward, and the top back- 50 wall section 6 slopes forward and comes flush with the top of the side wall of the corresponding rear edge of the latter, coinciding therewith. At the front of the side walls 5 are short upstanding portions 14 which are connected at the top by a cross piece 15 having bottom lugs adjacent to its 55 ends between which said part fits. The cross piece 15 has a depending apron 16 extending across the side walls 5 and serving as a baffle to deflect the smoke rearward to the flue and thereby prevent the same from entering the room. In case a grate is used the apron or depending portion may be dispensed with.

I claim:

1. A fireplace lining comprising opposite 65 side walls having ribs on their inner faces, and upstanding portions at their front ends, a rear wall comprising sections having grooved edges to interlock with the ribs of the side walls, and a cross piece connecting 70 said upstanding portions and having bottom lugs between which the latter fit, said cross piece also having a depending apron extending across the side walls at the top thereof.

2. A fireplace lining comprising opposite 75 side walls having ribs on their inner faces, top and bottom rear wall sections, said sections having grooved edges to interlock with the ribs of the side walls, and the rear faces 80 of the sections having edge recesses leading to the grooves.

In testimony whereof I affix my signature in presence of two witnesses.

GEORGE B. HAGGARD.

Witnesses:

EMILY F. CAMP,
MARGERY C. LUCAS.
